[57] CLAIM

The ornamental design for a small animal holder for use with apparatus measuring blood pressure of small animal, as shown and described.

DESCRIPTION

FIG. 1 is a perspective view showing a small animal holder for use with an apparatus measuring the blood pressure of a small animal showing my new design; FIG. 2 is a side elevational view thereof;

FIG. 3 is a top plan view thereof;

FIG. 4 is a left end view thereof;

FIG. 5 is a right end view thereof; and

FIG. 6 is a bottom plan view thereof.

FIG. 1

FIG. 2

FIG. 3

FIG. 5

FIG. 4

FIG. 6
